HOWARD D. COLMAN, OF ROCKFORD, ILLINOIS, ASSIGNOR TO BARBER-COLMAN COMPANY, OF ROCKFORD, ILLINOIS, A CORPORATION OF ILLINOIS

BALL-WARPER TRAVERSE MECHANISM

Application filed April 19, 1928. Serial No. 271,203.

This invention relates to machines for producing a cross-wound ball of warp yarn which has been gathered into an untwisted "chain." In such a machine or ball warper, 5 the chain is conducted to the ball by means of a guide or "trumpet" which is reciprocated longitudinally of the ball. Before the travel of the guide is reversed at the ends of the ball, the guide is necessarily caused to slow down. 10 As a result of such slowing down of the guide, more yarn is wound on the end portions of the ball than on the intermediate portion, the tendency, therefore, being to make the ends of the ball of somewhat larger diameter than 15 the main portion of the ball. This is particularly objectionable when it is necessary that the ball be wound under considerable pressure, as is the case with high-speed warpers such as those shown, for example, in Patent No. 20 1,336,447, dated January 25, 1921, and Patent #1,741,757, dated December 31, 1929. The pressure of the means employed to prevent bounding of the ball is applied particularly to the built-up end portions and results in causing 25 the ends of the ball to bulge. The bulging yarn usually becomes quite loose and may tangle during the subsequent step of unwinding the yarn. Moreover, while the ball is being handled or transported in the mill, the 30 loose-bulging yarn is liable to become soiled, snarled and broken.

The primary object of the present invention is to provide improved mechanism for winding the chain on the ball in such a manner as to reduce to a minimum the tendency 35 to build up the ends of the ball.

Traverse mechanisms heretofore commonly employed embody one or more cam cylinders for reciprocating the guide or trumpet. Such mechanisms usually project in front of the warper to such an extent that it is inconvenient for the operative to reach the leasing comb. Hence it is an object of the present 45 invention to provide a traverse mechanism which shall not extend so far forward of the warper as to cause inconvenience to the operative.

A further object of the invention is to provide a traverse mechanism which may be

readily applied to and removed from a beam warper.

In the accompanying drawings, Figure 1 is a right-hand end view of a traverse mechanism embodying the features 55 of my invention, said mechanism being shown in operative relation to a warper, the latter being fragmentarily illustrated in dotted lines.

Fig. 2 is a transverse vertical section of the 60 traverse mechanism upon a larger scale than that of Fig. 1, the view being taken in the plane of line 2--2 of Fig. 3.

Fig. 3 is a front elevation of the traverse mechanism. 65

Fig. 4 is a plan view of the traverse mechanism with certain parts in section, a portion of the framework of the warper being shown in dotted lines.

Fig. 5 is a fragmentary front elevation 70 of the traverse mechanism, the character of the wind produced thereby being illustrated diagrammatically.

Fig. 6 is a transverse vertical section in the plane of line 6--6 of Fig. 4. 75

In Fig. 1, A denotes the friction drum by means of which the ball B is revolved. The ball of yarn is wound upon a headless beain or "log" C which is supported in such a manner as to permit the ball to rest upon the periphery of the drum A. Reference may be made to said Patent No. 1,336,447 for an understanding of the manner in which the ball is supported upon the driving dirum A and the means by which the ball is pressed against 80 the drum. 85

The traverse mechanism comprises an elongated framework 1 adapted to be positioned in front of a beam warper and provided with rollers 2 by means of which said framework is supported upon the floor. The framework 1 is rigidly secured to the lower forward portion of the framework of the warper by means of screws 3 (Figs. 2 and 4) which extend through lugs 4 on the framework 1 and into 95 threaded holes in the framework of the warp-er. The lower forward portion of the warp-er framework is indicated in dotted lines D in Figs. 1, 2 and 4.

The traverse mechanism includes a car- 100

riage 5 slidably mounted upon two parallel guide rods 6 extending parallel with the axis of the friction driving drum A. The carriage 5 is reciprocated by means including a sprocket chain 7 carried upon two sprocket wheels 8 and 9, the carriage 5 being connected to the chain at 10 by means of a connecting rod 11. Rigidly connected to the sprocket wheel 9 is a bevel gear 12 (Fig. 1) that meshes with a bevel gear 13. The latter is rigid with a bevel gear 14 that meshes with a bevel gear 15. The gear 15 is fixed upon a shaft 16 upon which is secured a spur gear 17 which meshes with an intermediate gear 18, the latter in turn meshing with a pinion 19 fast upon the right-hand end of the shaft E of the driving drum A.

In order that slack in the chain may be taken up, the sprocket wheel 8 is mounted upon a stud 20 (Fig. 4) which is carried upon a slide 21 mounted in guideways 22 (Fig. 6) for adjustment longitudinally of the frame 1. The carriage 21 is clamped in adjusted position by means of clamping pieces 23. A coiled contractile spring 24 attached at one end to the slide 21 and at its other end to a tension-adjustment bolt 25 tends to move the slide 21 in the direction to take slack out of the chain 7. When it is necessary to tighten the chain 7 it will ordinarily be necessary merely to loosen the clamping pieces 23 and permit the spring 24 to move the slide 21 to the left, after which the clamping pieces 23 may be tightened to hold the slide 21 firmly in place. When necessary, the bolt 25 may be operated to increase the spring tension.

Rails 26 and 27 (Figs. 2 and 3) secured in the framework 1 underlie the upper and lower runs of the chain and prevent the latter from sagging.

The yarn guide or trumpet 28 (Fig. 2) is secured to the upper end of an arm 29 which is pivoted in the carriage 5 to swing upon the axis 30. Rigid with the arm 29 is a crank arm 31 carrying a cam follower roller 32 that runs in a guide groove. The major portion 33 of said guide groove is straight, being defined by two parallel bars 34 (Figs. 2 and 5) which are rigidly secured by means of screws 35 (Fig. 4) to a bar 36 forming part of the framework 1. The end portions 37 and 38 (Fig. 5) of the guide groove are formed in cam bars 39 and 40. The cam bar 39 is rigidly secured to the frame bar 36 by means of screws 41. The cam bar 40 is rigidly attached to the slide 21 by means of screws 42 (Figs. 5 and 6). The cam bar 40 is adjustably secured to the frame bar 36 by means of screws 43 (Figs. 3, 4 and 5) which extend through slots 44 in the cam bar and into treaded openings in the bar 36. The screws 43 serve as guide studs to maintain the right-hand end of the cam groove 38 in alignment with the left-hand end of the straight or dwell portion 33 of the guide groove. The cam

groove 37 is of such form as to swing the arm 29 on its pivot 30 toward the right as the guide is nearing the right-hand end of its travel, whereas the cam groove 38 is so shaped as to cause the arm 29 to swing toward the left as it nears the left-hand end of its path.

The operation of the traverse mechanism and the character of the wind produced thereby will be best understood by reference to Fig. 5. While the pivot 10 is moving from the point α to the point γ the speed of the carriage is gradually reduced to zero. When the pivot 10 is at the point α the roller 32 is about to enter the cam groove 37. Said cam groove is of such form as to cause the speed of the thread guide to be different from that of the carriage. In the particular embodiment herein shown of the invention, the cam groove 37 is so shaped as to cause acceleration of the yarn guide 28 notwithstanding the fact that the carriage 5 is decelerated. The acceleration of the thread guide produced by the cam groove 37 is relatively rapid at first and then decreases as the carriage approaches the extreme right-hand end of its travel.

Just before the carriage reverses its direction of motion, the guide 28 is sharply retarded or decelerated. A reverse operation of the thread guide occurs as the pivot 10 moves from the point γ to the point α .

Due to the acceleration of the thread guide while the chain is being laid in the region α' in Fig. 5, less yarn is laid upon the ball per unit length of ball than during the winding of the portions at either side of the region α' , thus producing in the region α' a less densely-wound section. Because of the lag of the chain between the guide 28 and the point of contact of the chain and the ball, slightly more yarn is laid in the extreme end region α^2 than on an equivalent length of the main portion of the ball, notwithstanding the sharp reversal of the guide. The pressure of the ball against the friction drum A causes the more densely-wound end portion α^2 to squeeze into the less densely-wound region α' as well as to bulge out somewhat at the end of the ball, such bulging being so slight as not to be objectionable.

The guide 28 is similarly actuated at the opposite end of its travel.

The chain makes a relatively sharp bend as its motion is reversed, the bend being sharper than in certain traverse mechanisms of the prior art. It will be understood that as the ball increases in diameter, the bend occupies fewer degrees of the circumference of the ball.

It will be apparent from Fig. 1 that the traverse mechanism extends but little beyond the vertical plane of the forward side of the ball and hence does not cause inconvenience to the operative.

Being self-contained and readily detachable from the warper, the traverse mechanism

may be removed when yarn is to be wound upon section beams, and replaced when warps are to be balled.

I claim as my invention:

1. A ball warper traverse mechanism comprising a carriage, means for reciprocating said carriage, an arm pivoted on said carriage, a yarn guide on said arm, means having a groove extending along the path of said carriage, the ends of said groove being of cam formation, and cam engaging means connected to said arm and traveling in said groove, the cam portions of said groove being of such formation as to cause acceleration of the yarn guide as the carriage approaches the ends of its travel.

2. A ball warper traverse mechanism comprising a carriage, means for reciprocating said carriage, an arm pivoted on said carriage, a yarn guide on said arm, means having a cam extending along the path of said carriage, and a crank arm connected to the first mentioned arm and engaging said cam, the end portions of said cam being of such formation as to cause acceleration of the yarn guide as the carriage approaches the ends of its travel.

3. A ball warper traverse mechanism comprising a carriage, means for reciprocating said carriage, a yarn guide movably supported on said carriage, and cams near the ends of the path of said carriage, said cams being of such formation as to cause acceleration of the yarn guide as the carriage approaches the ends of its travel.

4. A ball warper traverse mechanism comprising a carriage, means for reciprocating said carriage, said means acting to decelerate the carriage at the ends of its travel, a yarn guide movably supported on said carriage, cam means extending along the path of the carriage, and cam-engaging means connected to the guide, said cam means causing the speed of the yarn guide at the ends of its travel to be different from that of the carriage.

5. The combination with a warper framework, of a self-contained ball-warper traverse mechanism comprising an elongated framework, rollers to support said elongated framework on the floor, means for detachably securing said elongated framework to the warper framework, traverse mechanism on said elongated framework, and means to drive said mechanism.

6. The combination with a warper comprising a supporting framework, means in said framework to support a beam, and means in said framework to rotate the beam, of a self-contained ball warper traverse mechanism comprising an elongated supporting framework, means for detachably securing the last mentioned framework to the lower forward portion of the warper framework, traverse mechanism on the elongated

framework, and means on said elongated framework for transmitting power from the beam-rotating means to the traverse mechanism.

In testimony whereof, I have hereunto af- 70 fixed my signature.

HOWARD D. COLMAN.
